UNITED STATES PATENT OFFICE

127,702

DESIGN FOR A TENPIN HOLDER OR SIMILAR ARTICLE

Michael Weiss, Brooklyn, N. Y., assignor to Transogram Company Inc., New York, N. Y., a corporation of Pennsylvania

Application March 19, 1941, Serial No. 99,716

Term of patent 7 years

To all whom it may concern:

Be it known that I, Michael Weiss, a citizen of the United States, residing at Brooklyn, in the county of Kings and State of New York, have invented a new, original, and ornamental Design for a Tenpin Holder or Similar Article, of which the following is a specification, reference being had to the accompanying drawing, forming part thereof.

In the drawing the single figure is a perspective view of a tenpin holder or similar article looking from one side thereof, the opposite side being identical, showing my new design.

I claim:

The ornamental design for a tenpin holder or similar article, substantially as shown and described.

MICHAEL WEISS.
